UNITED STATES PATENT OFFICE.

ROBERT J. CARSON, OF DIXON, ASSIGNOR OF ONE-HALF TO EDWARD RUTZ,
OF BELLEVILLE, ILLINOIS.

IRON OR STEEL FENCE-POST.

SPECIFICATION forming part of Letters Patent No. 293,225, dated February 12, 1884.

Application filed August 14, 1883. (No model.)

To all whom it may concern:

Be it known that I, ROBERT J. CARSON, residing at Dixon, in the county of Lee and State of Illinois, have invented certain new and useful Improvements in Iron or Steel Fence-Posts, of which the following, in connection with the accompanying drawings, is a specification.

In the drawings, Figure 1 is a side elevation of a fence-post embodying my invention. Fig. 2 is a cross-section of the same in the plane of the line $x x$, viewed in the direction indicated by the arrow there shown; and Fig. 3 is a section in the plane of the line $x' x'$.

Like letters of reference indicate like parts.

In its general structural plan the fence-post herein shown and described is similar to that shown and described in Letters Patent of the United States of America No. 278,220, granted to me the 22d day of May, 1883, for the improvements therein set forth.

My present invention has reference to certain details of construction, which may be employed with advantage for the purpose of connecting the base-plate and pegs with each other firmly and with facility.

It also relates to certain other novel features of construction, all of which will be hereinafter particularly set forth in my claims.

A represents the fence-post proper, and B is the base-plate. The fence-post I make of metal, in any well-known or suitable way, and attach it firmly to the base-plate.

The base-plate consists of a central portion, a , adapted to receive and support the post, and of arms or braces $a' a'$, which extend radially from the central part, a , a considerable way, and then extend downward and laterally, as shown at $a'' a''$, the parts $a'' a''$ being inclined and having their upper ends nearer to the central part of the base-piece than the lower ends are.

C C are ribs or flanges on the lateral edges of the parts $a'' a''$ of the arms $a' a'$. These parts $a'' a''$ are somewhat concave or grooved on their outer faces, as shown at $b b$, for the purpose hereinafter referred to.

D D are the pegs. On the vertical or lateral edges of these pegs I lay flanges $c c$, and these pegs are of such a width that they will clasp the flanges C C when the pegs D D are pushed or driven down over the parts $a'' a''$ of the arms $a' a'$. In other words, the pegs D D are flanged to overlap and engage the lateral edges of the parts $a'' a''$ of the arms $a' a'$.

To stiffen or strengthen the pegs D D, I make them curved or curvilinear in cross-section, so as to meet or fit the grooved or depressed outer faces of the parts $a'' a''$ of the arms $a' a'$.

As the pegs D D are to be driven into the ground by blows from a hammer, and are made of comparatively thin or light metal, their upper ends should be adapted to receive these blows without material injury. To adapt them to receive such blows without injury, I cap or head them by dipping or immersing these ends into molten metal a sufficient number of times to provide them with a supplemental thickness or head, and such a head will in practice serve the purpose intended.

In order to set the posts, I apply the posts proper to the base-plates, and then set these combined parts where the posts are to be located. I then drive the pegs D D down upon and over the parts $a'' a''$ of the arms $a' a'$ and into the ground, the said pegs being of such a length as to anchor the posts firmly in their proper positions.

Having thus described my invention, what I claim as new, and desire to secure by Letters Patent, is—

1. The fence-post base-piece B, consisting of a central portion, a , adapted to support the post, and of two or more radial arms, $a' a'$, having depending and inclined portions $a'' a''$, with the flanges or ribs C C on their vertical or lateral edges, in combination with the pegs D D, having on their vertical or lateral edges the flanges $c c$, adapted to engage or clasp the flanges or ribs C C, substantially as shown and described, and for the purpose set forth.

2. The pegs D D, made curved or curvi-linear between their vertical edges, and having on the said edges the flanges c c, in combination with the radial arms a' a'', curved inwardly on their outer faces, and provided with the flanges C C, substantially as and for the purposes specified.

In testimony that I claim the foregoing as my own I hereto affix my signature in presence of two witnesses.

ROBERT J. CARSON.
